In Canada January 31, 1933

3 Claims. (Cl. 257—150)

This invention relates to improvements in a heater and appertains particularly to a radiator unit of the so-called concealed type.

An object of the invention is to provide a concealed heater formed preferably of a single casting that includes at least a pair of laterally spaced parallel fluid chambers extending horizontally between end manifolds or headers.

A further object of the invention is to provide such a concealed heater unit with vertical transverse fins that bridge the space between the fluid chambers and extend beyond the outer edges of the chambers thereby forming a series of air flues or stacks in the centre that is surrounded by the heating fluid and free fins extending outwards.

A further object of the invention is to provide a concealed heating unit with transverse vertical fins forming vertical air flues between the laterally spaced horizontal fluid chambers and whose outer free edges can be brought contiguous to or into contact with an enclosing structure to provide additional half heated stacks with the accompanying saving of material and conservation of space that would be denied if enclosing walls or partitions were formed along the fins' free outer edges.

A further object of the invention is to provide a concealed heating unit in which a series of vertical stacks is completely surrounded by a fluid passage (the specially designed ends or headers being included as part of the continuous passage).

A still further object of the invention is the provision of a heater of the nature and for the purposes described that is characterized by structural simplicity, durability, compactness, efficiency and low cost of production whereby the same is rendered commercially desirable.

To the accomplishment of these and related objects as shall become apparent as the description proceeds, the invention resides in the construction, combination and arrangement of parts as shall be hereinafter more fully described illustrated in the accompanying drawing, and pointed out in the claims hereunto appended.

The invention will be best understood and can be more clearly described when reference is had to the drawing forming a part of this disclosure wherein like characters indicate like parts throughout the several views.

In the drawing:—

Figure 1 is a front elevation of the heater in a conventional concealed installation;

Figure 2 is a plan view of the heater unit;

Figure 3 is an end elevation;

Figure 4 is a vertical transverse section as taken on the line 4—4 of Figure 1;

Figures 5 and 6 are a fragmentary plan view and transverse vertical section respectively of a modified form of heater;

Figure 7 is a sectional elevation illustrating both vertical and horizontal coupling of the heater units; and

Figure 8 is a similar sectional elevation showing an alternative form of vertical coupling.

This concealed heater is a one piece cast iron unit of square or rectangular cross section and of even dimensions throughout its considerable length. The length of the unit may be from 12 or 14 inches and upwards or larger units may be substituted by a number of smaller standard units that are readily coupled either vertically or horizontally to suit the space available. The conserving of space is one of the principal advantages of this heater that possesses enormous heating surface in proportion to its over all dimensions and the providing of free edge fins enables the unit to be placed contiguous to or even in contact with the front and back enclosing walls while still employing the heat conduction surfaces to the fullest advantage. The series of vertical centre stacks set up positive convection currents, to further which the fluid chambers are tapered slightly toward the top to permit of the normal expansion of the heated air passing therethrough. The draft or current of warm air passing upwards through the central stacks will naturally be more rapid and consequently of greater volume than through the stacks or passages established by the free edges of the fins being placed near the front and back enclosing walls but serves to accelerate the outside currents, the outer currents being led by the stronger central one.

The one piece cast iron unit 10 has an upright rectangular header 11 at each end with two threaded openings 12, one near the top and one near the bottom extending longitudinally through the header's end wall, being vertically aligned and centrally of the sides. The headers 11 are also each provided with a threaded opening 13 through the top wall and through the bottom wall, centrally of the sides and aligned with the passage or chamber in the header producing thereby a complete straight vertical passage through the end manifold or header. An annular thickened portion 14 surrounds each of the vertical openings 13 to give the necessary material for the threading to receive the coupling and serve as vertical spacers when the units may

be so assembled. They also serve a purpose when used with the supporting bracket to which reference will be made later.

Fluid chambers 15 join the headers 11, two or more extending horizontally between the headers, being laterally spaced from each other and vertically elongated. The outer side walls of the chambers 15 (or of the two outside chambers if more than two are used) lie flush with the side walls of the headers and the fluid chambers are also of the same height as the headers so that the whole skeleton appears as a pair of spaced boxes standing on end with their front and back sides continued to meet each other thereby enclosing within the boxlike headers and the relatively thin vertical fluid chambers a long narrow deep flue or stack 16 entirely surrounded by a fluid containing housing.

Longitudinally spaced vertical transverse fins 17 are cast integral with the structure and are of the same height as the longitudinal fluid chambers 15 and headers 11. The series of these fins extends the full length of the casting and though interrupted by the headers, bridge the flue 16 separating them, dividing it into a plurality of air flues or stacks. They also extend out the sides a distance equal to substantially one half the distance between the laterally spaced fluid chambers 15 and their outer edges are free. The end fins 18, flush with the opposite ends of the headers may be thickened, if desired, for greater strength against breakage or to provide adequate material for receiving supporting legs. The fluid chambers 15 will preferably taper vertically to prevent steam from trapping or water from becoming air bound and the outer walls thereof being of corresponding configuration aids in establishing the air current by allowing wider air passages toward the top of the flues for the expanded warm air, nevertheless the opposite free edges of the fins are parallel and perpendicular.

In Figures 5 and 6 the unit 20 is shown with three fluid chambers 21, the centre of which divides the general central air flue or stack 22 in two but here also it will be seen that the outer or free edges of the fins 22 remain in the same dimension relation to the distance between adjacent fluid chambers, being one half the length of one of the intermediate bridging portions.

In assembling several units, the vertical stacking may be accomplished by using left and right hand threaded nipples 24 inserted with a key in the adjacent vertical openings 13 or the usual oppositely threaded coupling 25 (shown in Figure 8) may be used. For horizontal or longitudinal couplings the hexagonal nipples 26 will preferably be employed.

The legs 27 threaded into the headers or end fins are useful when the inlet pipe 28 is brought in from the end as shown in Figure 1, but if it

comes in the bottom at one end and the outlet leads from the opposite end and an air line or valve 29 is employed, angle brackets 30 are better employed, their upper angle being forked with a semi-circular recess that embraces the thickened reinforcement 14 and prevents lateral as well as longitudinal displacement of the unit.

This heater has been especially designed for hot water, vapor and low pressure steam heating systems, used with which it gives a maximum of 10 heating efficiency for the space occupied.

From the foregoing description taken in connection with the accompanying drawing, it will be manifest that a heater is provided that will fulfil all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawing shall be interpreted as illustrative and not in a limitative or restrictive sense.

Having thus described the invention, what is claimed as new is:—

1. A concealed heater unit comprising a single casting with end headers; laterally spaced, longitudinally extending and vertically elongated and tapered fluid chambers joining the headers and the top and bottom walls of all the chambers, the outer walls of the outside chambers being flush with the corresponding walls of the headers, and longitudinally spaced transverse vertical fins bridging the space between said chambers, and fins extending outwardly of the outer chambers a length substantially equal to half the distance between adjacent chambers, the outer edges of said last named fins being free.

2. A concealed heater unit having end headers, a vertical opening in the top and bottom of each header, an annular thickened reinforcement around each of said vertical openings; laterally spaced fluid chambers joining said headers, transverse vertical fins spaced throughout the length of said unit; and supporting angle brackets having their upper angle bifurcated with a semi-circular recess to accommodate said annular thickened reinforcements for holding said unit against displacement.

3. A concealed heater formed from a single casting having end manifolds and connecting fluid chambers forming a continuous fluid passage surrounding a vertical air flue or stack; and transverse vertical fins bridging said fluid chambers to divide said air flue or stack and fins extending outwardly beyond said fluid chambers a length substantially equal to half the distance between adjacent fluid chambers, the outer edges of said last named fins being free.
